UNITED STATES PATENT OFFICE

135,741

DESIGN FOR A HOUSING FOR RAPID TRAVERSE MECHANISM FOR LATHES

William M. McConnell, McKeesport, Pa., assignor to Mackintosh-Hemphill Company, Pittsburgh, Pa., a corporation of Delaware

Application August 21, 1942, Serial No. 107,984

Term of patent 14 years

To all whom it may concern:

Be it known that I, William M. McConnell, a citizen of the United States, residing in McKeesport, in the county of Allegheny and State of Pennsylvania, have invented a new, original, and ornamental Design for a Housing for Rapid Traverse Mechanism for Lathes, of which the following is a specification, reference being had to the accompanying drawing, forming a part thereof.

In the drawing:

Fig. I is a perspective view of a housing for rapid traverse mechanism for lathes showing my new design, the said rapid-traverse housing

being viewed from the rear and to one side thereof.

Fig. II is a perspective view of the said housing for rapid traverse mechanism for lathes viewed from the side opposite that shown in Fig. I. The end not shown is substantially plain.

The dominant features of the design are shown in full lines.

I claim:

The ornamental design for a housing for rapid traverse mechanism for lathes, substantially as shown and described.

WILLIAM M. McCONNELL.
